UNITED STATES PATENT OFFICE.

JAMES NEVIN, OF THOROLD, ONTARIO, CANADA.

ARTIFICIAL LEG.

1,372,365.

Specification of Letters Patent. Patented Mar. 22, 1921.

Application filed February 13, 1919. Serial No. 276,765.

To all whom it may concern:

Be it known that I, JAMES NEVIN, a subject of the King of Great Britain, and resident of the town of Thorold, in the county 5 of Welland, Province of Ontario, Canada, have invented certain new and useful Improvements in Artificial Legs, of which the following is a specification.

This invention relates to artificial legs 10 adapted for either above or below the knee amputations, and my object is to devise a simple and strong construction which will give a more natural and easier action than the present type of leg and which, therefore 15 will give greater comfort to the wearer.

I attain my object by means of an improved ankle joint construction and by so arranging the joints of the leg that, when the wearer is standing upright with all 20 parts of the artificial leg free to assume their normal positions, the axis of the knee joint is forward of the vertical plane in which the axis of the ankle joint lies and a spring is provided tending to resist the bending 25 at the knee joint when the wearer's weight is on the artificial leg.

The constructions referred to and other improvements in the details of construction are illustrated in the accompanying 30 drawings in which—

Figure 1 is a vertical section of an artificial leg constructed in accordance with my invention, the leg being shown in the position it assumes when the wearer is standing 35 upright on both feet;

Fig. 2 a similar view showing the leg bent at the knee joint in the position it assumes when the wearer is sitting;

Fig. 3 a side elevation showing a modified 40 form of the spring connection between the thigh and shank portions of the leg;

Fig. 4 a similar view showing a further modification such as used with below the knee amputations;

Fig. 5 a rear view, partly broken away, of 45 parts shown in Fig. 3.

In the drawings like numerals of reference indicate corresponding parts in the different figures.

Referring particularly to Figs. 1 and 2, 50 1 is the thigh portion of the leg, 2 the shank portion and 3 the foot. These parts may be constructed in any ordinary manner known to the art.

55 The foot is pivotally connected with the

shank portion by means of the pivot pin 4, which is secured to one of the parts which it connects and passes through a vertical slot formed in the other. Preferably the slot 5 is formed within the sides of the 60 lower parts of the side irons 6 of the shank portion. Both in front of and behind the pivot pin opposed shoulders 7 are formed on the foot and shank portions, and between those shoulders are placed rubber cushions 65 8. To hold the parts in contact, which is necessary in view of the fact that the pivot pin works in a slot, I provide the flexible cord 9, which passes over a guide roller 10 journalized in the shank portion. The ends 70 of this cord are secured to the front portion and spring tension means are provided for this cord or connector. In the preferred arrangement, each end of the cord has a metal end piece 11 secured thereto, which is 75 threaded to receive a nut 12. The cord passes through alined holes in the shank portion cushions and foot, which holes open into recesses formed in the under side of the foot to receive coil springs 13, which springs 80 engage the shoulders 14 formed at the bottoms of the recesses and the nuts 12. By means of these nuts any suitable tension can be given to the cord. With this arrangement the necessary limited and elastically 85 cushioned rocking movement is provided for the ankle joint, and further a cushioning effect is obtained when the wearer is standing upright owing to the fact that the pivot pin operates in a vertical slot. Under all 90 conditions the parts are held in proper contact by the cord 9.

The vertical line drawn in Fig. 1 through the ankle joint is assumed to lie in a vertical plane in which lies the center of gravity of 95 the body of the wearer when he is standing erect on both feet. It will be noted that under these conditions, the axis of the pivot pin 15 which forms the knee joint lies in front of this vertical line. The result is that 100 the weight of the wearer tends to flex the knee joint, which is exactly the opposite arrangement to that commonly adopted in which the knee joint under these conditions is practically rigid, while either in the vertical plane in which the ankle joint and the center of gravity of the body of the wearer lie or behind the same. As the weight of the wearer thus tends to flex the knee joint, it is necessary to provide means for limiting 110

this movement, and to obtain the advantages I desire such limiting means must be resilient in their character.

In Figs. 1 and 2 I show an arrangement, 5 which may be considered as more or less diagrammatical, for the purposes of illustration. A coil spring 16 is carried by a bracket within the shank portion of the leg. A connecting rod 17 is pivotally connected with 10 the thigh portion of the leg and has an end 18 adapted to engage the upper end of the coil spring. This connecting rod passes through a slide 19, which passes through the back of the shell of the shank portion of the 15 leg and has a button secured thereto.

As will be seen from the drawings, the end of the connecting rod may by the operation of the slide be either brought into engagement with the upper end of the spring 20 16 or pushed out of engagement therewith. When the parts are in the position shown in Fig. 1, the necessary spring cushion between the thigh and the shank portion of the leg is provided. When the wearer desires to 25 sit down, the connecting rod may be pushed forward as shown in Fig. 2, when the leg will flex unrestrained at the knee joint.

In Fig. 4 I show an arrangement which is best adapted for below-the-knee amputations when it is not possible to place any mechanism within the shell of the shank portion of the leg. In this case the thigh portion terminates in the side irons 20 pivoted on the shank portion of the leg. A 30 yoke 21 extends forwardly from these side irons and is provided with an eye 22 to which is connected a cord or wire 23, which passes through and is suitably secured to the lower end of a compression coil spring 24. 35 A fork 25 is secured to the front of the shank portion of the leg and with this fork the upper end of the coil spring 24 is engaged when the wearer is walking. When the wearer desires to sit down, the coil spring 40 is readily disengaged from the fork and the leg left free to flex at the knee joint.

I find that with the constructions described the leg is much more comfortable to use and approximates very much more 45 closely to the action of the natural leg than other artificial legs which I have used or with which I am acquainted.

In Fig. 3 I show a preferred construction of the spring connection. The spring 26 is 50 of the semi-elliptic type and its ends are slidable on a guide plate 27 secured to the thigh portion of the leg. In the shank portion of the leg is journaled a shaft 28 on which is secured an arm 29 adapted to be 55 brought into engagement with the spring as shown in full lines in Fig. 3, or tipped back as shown in dotted lines when the wearer of the leg desires to sit down. To operate the shaft I provide at one end a 60 lever 30. This lever is provided with a lug

31 which is engageable by the slip pin 32 movable in guide lugs 33 formed in a plate secured to the outside of the shell of the shank portion of the leg. By moving this slip pin lengthwise, the lever arm 30 is released or engaged and held as may be desired.

It will be found that the whole action of my leg is entirely different from the ordinary leg in which the knee is rigid and non-resilient when the wearer's weight is upon it, and which, therefore, produces a disagreeable drag upon the stump when the leg is brought up from behind. When the wearer's weight is on my leg, the leg automatically flexes slightly both at the ankle and knee and automatically extends when the wearer's weight is taken off, thus making the action of bringing the leg forward more easy and natural, involving less abnormal 80 muscular action on the part of the stump.

What I claim as my invention is:

1. An artificial leg jointed at the knee and the ankle, the axis of said knee joint being forward of the center of gravity of 90 the wearer's body, and manually releasable cushioning means normally elastically limiting the bending at the knee joint when the wearer's weight is on the leg.

2. An artificial leg jointed at the knee 95 and the ankle, the axis of said knee joint being forward of the center of gravity of the wearer's body, in combination with a manually releasable spring connection between the parts of the leg above and below 100 the knee joint tending to resist bending at the knee joint and to support the wearer's weight.

3. An artificial leg jointed at the knee and the ankle, the axis of said knee joint 105 being forward of the center of gravity of the wearer's body, in combination with a manually releasable spring connection between the parts of the leg above and below 110 the knee joint tending to resist bending at the knee joint and to support the wearer's weight, and spring means permitting a limited rocking movement of the foot on the ankle joint.

4. In an artificial leg, the combination of 115 a foot; a shank portion; a pivot pin secured to one of said parts and passing through a vertical slot formed in the other part to form an ankle joint; opposed shoulders formed on said parts both in front of and 120 behind the pivot pin; resilient cushions fitted between said shoulders; and flexible spring means tending to draw the foot and shank portions together without interference with the rocking movement of the foot 125 on the shank.

5. In an artificial leg, the combination of 130 a foot; a shank portion; a pivot pin secured to one of said parts and passing through a vertical slot formed in the other

part to form an ankle joint; opposed shoulders formed on said parts both in front of and behind the pivot pin; resilient cushions fitted between said shoulders; a flexible connector engaged at its ends with the foot; a guide on the shank portion over which the connector is led; and spring tensioning means for the connector.

5 6. An artificial leg jointed at the knee and the ankle, the axis of said knee joint being forward of the center of gravity of the wearer's body, in combination with a compression spring and a manually releasable member movable into and out of operative engagement with said spring.

10 7. An artificial leg jointed at the knee and the ankle, the axis of said knee joint being forward of the center of gravity of the wearer's body, in combination with a compression spring, a shaft carried by part 20 of the leg, an arm carried by said shaft and

movable into and out of coöperative engagement with said spring, and manually operating means for releasably locking the arm in engagement with the spring.

25

8. An artificial leg jointed at the knee and the ankle, the axis of said knee joint being forward of the center of gravity of the wearer's body, in combination with a compression spring, a shaft suitably journaled, an arm secured to said shaft and movable by the rocking of the shaft into and out of coöperative engagement with the spring, an arm secured to the shaft outside the leg, and releasable locking means operated by said arm.

Signed at Thorold this 28th day of January, A. D. 1919.

JAMES NEVIN.
